[57] **CLAIM**

The ornamental design for an apparatus for removing smoke and liquid from a surgical site in a hospital operating room, as shown and described.

DESCRIPTION

FIG. 1 is a perspective view of an apparatus for removing smoke and liquid from a surgical site, showing our new design;

FIG. 2 is a front elevational view thereof;

FIG. 3 is a side elevational view thereof, the opposite side being a mirror image of that shown;

FIG. 4 is a rear elevational view thereof;

FIG. 5 is a top plan view thereof; and,

FIG. 6 is a bottom plan view thereof.

The cross-hatching in FIGS. 1,4,5 and 6 represents screening and is understood to extend through out the areas represented.

FIG.1

FIG.2

FIG.3
